UNITED STATES PATENT OFFICE.

CHARLES E. BENTLEY, OF NEW YORK, N. Y.

DESIGN FOR A BOTTLE.

SPECIFICATION forming part of Design No. 20,029, dated July 15, 1890.

Application filed June 3, 1890. Serial No. 354,139. Term of patent 7 years.

To all whom it may concern:

Be it known that I, CHARLES E. BENTLEY, a citizen of the United States, residing at the city of New York, county and State of New York, have invented and produced a new and original Design for a Bottle, of which the following is a specification, reference being had to the accompanying drawings, forming part thereof.

10 Figure 1 is a side view of a bottle embodying my design, and Fig. 2 is a plan view thereof, these two views being deemed necessary to fully illustrate the design.

15 The leading features of novelty of my design for a bottle or dressing-case ornament consists more particularly in the configuration of its lower body portion, which is surmounted by a comparatively long central neck or stem.

20 The body A of the bottle or ornament is surmounted by a central neck or stem a, which is shown slightly enlarged toward the top, but may be cylindrical or of like diameter throughout. The body is preferably made

25 a little higher than it is wide, and from the base or root of the neck or stem its sides 1

extend downward and outward by a gradually-curved but quick-sloping outline to the largest diameter of the body, which is quite low down at a point 2, whence its lower part 30 3 curves downward and inward to the bottom or base line 4 of the bottle. The body thus is pear-shaped in general outline, as viewed from the side and shown in Fig. 1 of the drawings. The entire side surface of the body from 35 the neck or stem to its base is divided by radially and vertically ranging depressions 5, so as to produce a series of horizontally-convex and vertically-ranging lobe-like projecting sections 6, which are rounded over at 40 the top into the neck of the bottle or ornament and give it the pleasing appearance represented in the drawings.

An ordinary cut-glass stopper is shown in the neck or stem of the bottle. 45

I claim as my invention—

The design for a bottle, substantially as herein shown and described.

CHARLES E. BENTLEY.
